UNITED STATES PATENT OFFICE.

NICOLAS KOMOW, OF NEW YORK, N. Y., ASSIGNOR TO THE UNITED STATES CLOTH CUTTING MACHINE CO. INC., OF NEW YORK, N. Y.

ELECTRIC CLOTH-CUTTING MACHINE.

1,141,087.

Specification of Letters Patent. Patented May 25, 1915.

Application filed July 24, 1912, Serial No. 711,321. Renewed January 23, 1915. Serial No. 4,077.

To all whom it may concern:

Be it known that I, NICOLAS KOMOW, a citizen of the United States, residing at Brooklyn, in the county of Kings, city and State of New York, have invented a new and useful Electric Cloth-Cutting Machine, of which the following is a specification.

My invention relates to improvements in electric cloth cutting machines, in which a circular knife is driven by an electric motor, by means of a set of gears, and the objects of my improvements are, first: to provide a machine with a compact motor, which does not obstruct the view of the knife; second: to afford facilities for the grinding of the circular knife; third: to have an effective guard which will protect the operator from injury by the knife; fourth: novel means of raising the cloth so as to bring the bottom layers up against the edge of the knife, so that the bottom layer may be cut as deep as the top, while cutting around corners. I attain these objects by mechanism illustrated in the accompanying drawing, in which—

Figure 1, is a front view of the entire machine. Fig. 2, is a side view of the entire machine. Fig. 3, is a top view of the part of the base 1, auxiliary cloth-raiser 3 and movable cloth-raiser 4, and recess 5. Fig. 4, is top view of the motor part showing the field-magnets, field-coil, armature and shaft. Fig. 5, is a top view of a field lamination. Fig. 6, is a front view of the gear-guard 22, spring 23, showing means of attaching the same to standard 2, and bottom cup 25. Fig. 7, is a side view of knife-guard 17, set screw 18, and rod 11 on which it is adjusted.

Similar numbers refer to similar parts throughout the several views.

To the base plate 1 is fastened the standard 2 to which is movably fastened a circular knife 19 by means of the screws 10 and 11.

The bevel gear 20 and the flange 8 are fixed to the circular knife 19. The gear 21, which is fixed to the armature shaft 30, engages the gear 20 and revolves the knife by the rotation of the armature 29.

In the base plate 1 I make a recess 5 in which is movably set the cloth raiser 4, behind the stationary cloth raiser 3. The movable cloth raiser 4 is fulcrumed at 4'. At the rear of the cloth raiser 4, rests the pressing rod 80 which bears in the lugs 6

and 7 of the standard 2. The lower end of the coil spring 9 rests on the lug 6 and the upper extremity presses against the knob 100, which is at the upper extremity of the pressing rod 80. The pressure of the spring 9 normally tends to keep the rod 80 in its raised position.

It has been found to be impossible to make vertical cuts in layers of cloth while going around curves or into corners with a circular knife and in order to make vertical cuts in layers of cloth while going around curves or into corners, I press the knob 100 at the upper extremity of the rod 80, thus overcoming the upper pressure of the spring 9, and forcing the shorter end of the movable raiser 4 downward, raising the forward plow-shaped end upward, thus raising the cloth and bringing it nearer to the center of the knife. On straight cuts, the stationary cloth raiser which is fixed to the base in front of the knife, raises the cloth sufficiently high to prevent the knife from drawing the cloth in too quickly. When the movable cloth raiser is in its raised position, the stationary cloth raiser 3 prevents the forward point of the movable cloth raiser 4 from digging into the cloth.

The knife guard 17 is movably mounted on the rack rod 110 and is adjusted by a set screw 18 so as to expose more or less of the edge of the knife, according to the thickness of the cloth to be cut.

The back rod 110 bears in the lugs 13 and 14 of the standard 2. At the forward end of said rod 110 is the rack 12 which engages the pinion 15. Said pinion 15 is mounted on the grinder 16 and swivels on the pin 15'.

One end of the spring 16' is fastened to the bottom cup 25, and the other end is fastened to the grinder 16 so as to keep the grinder in the upward position, away from the knife when not in operation. To sharpen the knife 19, I pull the hook 110' of the rod 110, which brings the guard 17 backward and exposes the edge of the knife, and simultaneously the rack 12 engages the gear 15 and turns it so as to bring the grinder down against the knife, overcoming the tension of the spring 16'. The removable gear guard 22 is held in place by the spring 23 and the lug 2' of the standard 2.

The spring 23 is fastened to the bottom cup 25, at 24. The method of fastening

makes the gear guard 22 easily removable for the purpose of cleaning and oiling the gear 21.

Having thus described my invention, 5 which I claim as new, and desire to secure by Letters Patent is:

1. In an electric cloth cutting machine the combination with the base plate standard, circular knife and means of operating same 10 of a movable cloth-raiser fulcrumed and raised by means of a pressing rod and released by a spring and a stationary cloth-raiser set in front of movable cloth-raiser substantially as set forth.
- 15 2. In an electric cloth cutting machine, the combination with a base-plate, standard,

circular knife and means of operating the same and an automatic grinder having a gear mounted on its casing, of a rack on a grinder rod engaging said gear, and a tension spring adapted to hold said grinder up, substantially as described. 20

3. In an electric cloth cutting machine, the combination with a base-plate, standard, circular knife and means of operating the 25 same, of a grinder rack rod, and a movable knife guard adjustably mounted thereon, substantially as described.

NICOLAS KOMOW.
